J. L. Krauser,

Making Cut Nails,

N° 20,312.

Patented May 18, 1858.

UNITED STATES PATENT OFFICE.

JOHN L. KRAUSER, OF READING, ASSIGNOR TO HIMSELF, AND JAMES HARPER, OF PHILADELPHIA, PENNSYLVANIA.

IMPROVED NAIL-MACHINE.

Specification forming part of Letters Patent No. 20,312, dated May 18, 1858.

To all whom it may concern:

Be it known that I, JOHN L. KRAUSER, of Reading, in the county of Berks and State of Pennsylvania, have invented certain new and useful Improvements in Nail Machinery; and I do hereby declare the following to be a full, clear, and exact description of the construction and operation of the same, reference being had to the accompanying drawings, making a part of this specification, in which—

Figure 1 represents a perspective view of the machine. Fig. 2 represents a detached elevation of the rolls for rolling the nail-plate. Fig. 3 represents a vertical section through the anvil-block and its cutter and the feeding-trough. Fig. 4 represents a front view of the anvil-block and cutter. Fig. 5 represents a top plan of the anvil-block and its cutter, and showing in red lines the oscillation of said anvil-block. Fig. 6 represents a side view of one of the nail-plates with the shape of the nails cut from it in dotted lines. Fig. 7 represents a vertical transverse section through the nail-plate shown in Fig. 6.

Similar letters of reference, where they occur in the several figures, denote like parts of the machine in all the drawings.

I am aware that a rotating disk cutter and vibrating anvil have long been known in nail machinery, but which, from many defects in their construction and operation, have not been generally introduced. These defects I propose and believe I have entirely obviated, my machine, by a simple change of cutters, being capable of making nails of different sizes and forms, inasmuch as I need not use a heading apparatus, while I can cut a nail having a head on all four of its sides, which, so far as I know or can learn, has never heretofore been accomplished.

My invention may be said therefore to relate to that class of nail-machines in which a rotary disk cutter and a vibrating anvil are used, the special points of novelty in which and its product I shall hereinafter fully explain.

To enable others skilled in the art to make and use my invention, I will proceed to describe the same with reference to the drawings.

A represents a substantial frame, in which is hung a shaft B, that is rotated by any first

moving power by belt or gearing. On this shaft is permanently fixed a disk or wheel C, to which is affixed the cutter stocks or blocks D for holding the adjustable and removable cutters 1 2 3, (there being two sets,) set at opposite inclinations to each other on said disk for cutting the "nail head and point," as it is termed. On opposite sides of the perimeter of the disk or wheel C there are gage plates or segments E E, which are adjustable by slots and set-screws, as seen at a a. The object of these plates is to gage the feed of the nail-plate, and consequently the width of the nail to be cut from it.

In a suitable pillow-block F on the bed G of the machine is supported the shank or journal H of an anvil I, so that the anvil may freely vibrate in its bearings. That side of the anvil-block next the disk-wheel C is cut away, as shown in Fig. 3, so that the cutting-edge b of its cutter J shall have its center of vibration at or near the vertical line of motion of the journal or shank of said anvil, as shown by the red lines of Figs. 3 and 5. The object of so hanging the anvil-cutter is to prevent any wear or looseness in the anvil connections from multiplying its error, as it will do when connected to and vibrating upon a point in its rear, or anywhere not immediately underneath the cutting-edge, the motion at the center of vibration being less than at any other point in its vibration, and all irregular motions at the center increasing in an exceeding great ratio from that point to the circumference. Besides this advantage I still have the journal-bearing of the anvil far enough from its face to prevent the heat from effecting its lubrication, and it is also effectually protected from the dropping scales, which would otherwise cut and wear its bearings. These are important features, because if the anvil does not vibrate on true points there will be no uniformity in the shape of the nails. The anvil and its cutter must also incline downward as it recedes from the cutting-point, so that as the nail-plate is fed up it will lie upon the cutter fairly that the rotating cutters may readily sever the nail therefrom.

The anvil I and its cutter J are vibrated as follows: A cam K on the shaft B works between the arms c c of a lever L, pivoted to

the frame A. To an arm of this lever, projecting below its pivoted point, is attached one end of a pitman M, the other end of said pitman being similarly pivoted to an arm N, projecting from the shank H of the anvil, and thus every revolution of the shaft B imparts two vibrations to the anvil, there being two nails cut at every revolution of the shaft.

In the cutter J, which is set in the anvil I, there must be grooves 45 to receive the flanges on the nail-plate, as represented at Figs. 6 and 7. If there be two flanges on the lower and upper sides of the plate, as shown in said Figs. 6 and 7, then there must be two grooves in the cutter J; but there need not be any grooves to receive the flanges on the upper side of the nail-plate. If there be but one set of flanges, then one groove will answer. If the flanges on the nail-plate only project on one of its sides, there need be no grooves in the cutter, as the flat side of the plate may come next the cutter; or, if found desirable, the groove may in some cases be in the feed or nail-plate holder.

O is the trough through which the nail-plate is fed up to the cutters by a cross-head P, moving on a rod d and on ways e e, said cross-head being forced toward the cutters (and carrying with it the nail-plate) by the uncoiling of the spring f from its drum g, or it may be done by a falling weight or other known mechanism for this purpose.

h is a bent rod, by which the cross-head or nail-plate feeder is drawn back behind the fresh nail-plate when the previous one is fed up, and to prevent the feeder from dragging back the plate with it two springs rise up in the bed of the trough behind the plate, which prevent it from slipping back, while the feeder may slip back for the next plate.

In the cross-head P there is a pivoted arm or lever i, Fig. 3, the point of which catches behind the nail-plate to force it up. The rear of this lever is raised and rounded off, which holds up the said rear portion and prevents it from catching against the new plate in being drawn back.

I have represented the rolls for rolling out

the nail-plates as connected and combined with the nail-cutting machinery, and driven from the shaft B, that operates the nail machinery; but I do not confine myself to this special combination of parts, because the rolling devices may be used separated from the other parts of the machine, as shown in Fig. 2, and the plates be rolled separate from the machine wherein they are to be cut, and they may be connected or disconnected, as the user prefers.

The rollers R S T U for forming the nail-plate do not differ from those ordinarily used for rolling similar forms, except perhaps in size, and are well known to mechanics. Of course other forms of rolls may be used that will produce the particular form of plate desired.

In cutting nails with heads on all four of their sides there is no loss of material, as will be seen at Fig. 6, when the cutters are properly adjusted for it; and from the plates of other forms one, two, or three sides of the nail may only have heads on.

Having thus fully described the nature and object of my invention, what I claim therein as new, and desire to secure by Letters Patent, is—

1. Forming a groove or grooves in the anvil-cutter to receive the flange or flanges on the nail-plates, as set forth.
2. In combination with a vibrating anvil or anvil-cutter, the placing of the cutting-edge of said cutter at or near the center of motion of said vibration, in the manner and for the purpose set forth.
3. The rims or adjustable sections E on the perimeter of the rotating cutter-wheel C for regulating the size of the nail to be cut, as set forth.
4. In combination with a rotating cutter-wheel and a vibrating anvil, the inclination given to said anvil and its cutter, for the purposes herein stated.

JOHN L. KRAUSER.
